WINDOW CONSTRUCTION

Filed Feb. 24, 1927

UNITED STATES PATENT OFFICE

FRED E. WEBB, OF WATERTOWN, NEW YORK

WINDOW CONSTRUCTION

Application filed February 24, 1927. Serial No. 170,530.

The invention relates to windows having sliding sash members and has for its object the provision of means by which the sash frames are detachably secured to sliding bars 5 of the window frame to enable ready removal of the sash members from the window frame for cleaning or repair.

A further object of the invention is the provision of a window construction including 10 a window frame having grooves in its stiles in which are slidably mounted bars connected with the counterweights or other means for holding the sash in adjusted position, and providing the sash members with grooves 15 in their stiles to receive the bars, and means carried by the sash members to secure the members to the bars for movement therewith, the construction admitting of attachment of the sash members from the bars for removal 20 of the sash members from the frame for cleaning or repair.

The invention will be described in detail hereinafter and will be found illustrated in the accompanying drawings, in which

25 Figure 1 is a front view partly in section of a window frame showing one of the sashes in position and secured to one of the bars, the other bar being released from engagement with the sash and being shown in its raised 30 position,

Figure 2 is a vertical sectional view on a plane indicated by the line 2—2 of Figure 1, and

35 Figures 3 and 4 are sectional details on an enlarged scale on planes indicated by the lines 3—3, and 4—4 of Figure 1.

In the drawings similar reference characters will be used to designate corresponding parts throughout the several views.

40 The window frame is indicated at 1 and has spaced strips 2 secured to its stiles 3 providing grooves 4 therebetween in which are slidably mounted bars 5 having recesses 6 in their upper ends in which are secured sash cords 7 carrying counterweights 8 and trained over pulleys 9, or any other conventional construction of means for counteracting the weight of the sash may be employed, such 45 other means not being shown as the applica-

tion thereof is obvious and is considered to be unnecessary to specifically show and describe.

The window sash 10 is provided with 55 grooves 11 in its stiles to receive the bars 5, and 12 designates pins slidably engaging openings 13 in the sash stiles that engage in recesses 14 of the bars 5 to hold the sash for movement with the bars. The upper ends of the stiles of the window sash 10 are provided with openings 15 to permit removal of the sash 10 from the window frame for repair or cleaning, and the upper ends of the bars 5 are provided with offsets 16 that engage in and fill the openings 15 when the 60 sash 10 is secured to the bars.

The advantages of the invention will be apparent as by the construction as shown and described it will be understood that the sash members of a window may be readily removed and replaced relatively to the frame, as the sash member 10 may be released from the sliding bars 5 by sliding the sash and attached bars 5 to the top of the frame. The pins 12 will then be withdrawn from engagement 75 with recesses 14 and the sash slid downwardly on the bars 5 to the lower part of the frame when it will be readily removable from the window frame, the openings 15 providing for removing the lower ends of bars 5 from 80 the grooves 11 when the sash is lowered relatively to the bars 5. When the sash is in the position secured to the bars 5 as indicated at the left side of the frame shown in Figure 1 the sash may be raised or lowered in the 85 frame and will be held in adjusted position by means of the counterweights 8 or other means for counteracting the weight of the sash member. Furthermore the offsets 16 provide 90 bearings for the bars 5 to prevent binding between the sash 10 and the strips 2.

What is claimed is:—

A window construction, comprising a frame having grooves in its stiles, bars slidably mounted in said grooves, a sash member 95 having grooves in its side members to receive said bars and openings in the side members communicating with the grooves, means to secure the sash member to the bars, and offsets on the bars to seat in the openings in the sash 100

member, said offsets providing bearings for the bars slidably engaging the frame on the sides of the grooves therein to prevent the sash member from binding in the frame during sliding movement thereof.

5 In testimony whereof I affix my signature.

FRED E. WEBB.
